US00D914648S

(12) **United States Design Patent** (10) Patent No.: **US D914,648 S**
(45) Date of Patent: **** Mar. 30, 2021**

(54) **EARPHONE**

(71) Applicant: **Wenjie Zhou**, Henan (CN)

(72) Inventor: **Wenjie Zhou**, Henan (CN)

(**) Term: **15 Years**

(21) Appl. No.: **29/746,653**

(22) Filed: **Aug. 15, 2020**

(51) LOC (13) Cl. **14-01**

(52) U.S. Cl.

USPC **D14/223**

(58) **Field of Classification Search**

USPC D14/223, 205; D24/174; 128/864, 865,
128/866; 381/380, 381; 455/90.3, 575.1,
455/569.1

CPC H04R 1/10; H04R 25/00; H04R 25/02;
H04R 1/1066; H04R 1/1016; H04R
5/033; H04R 5/0335

Primary Examiner — Paula Allen Greene

(74) Attorney, Agent, or Firm — Erson IP (Nelson IP)

(57) **CLAIM**

The ornamental design for earphone, as shown and described.

DESCRIPTION

FIG. 1 is a front elevational view thereof;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof; and,
FIG. 7 is a perspective view of a earphone showing my new design.

1 Claim, 7 Drawing Sheets
